CLAIM

The ornamental design for a fender flare, as shown and described.

DESCRIPTION

FIG. 1 is a perspective view showing top and front surfaces of a fender flare.

FIG. 2 is a perspective view showing bottom and rear surfaces thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings illustrate portions of the fender flares which form no part of the claimed design. Certain features, such as fasteners, fastener holes, mounting structures and cut-out logos are shown in broken lines and disclaimed.
